UNITED STATES PATENT OFFICE.

RUDOLF SCHMITT, OF FRANKFORT-ON-THE-MAIN, GERMANY, ASSIGNOR TO THE FIRM OF MASCHINENFABRIK SCHNARR & SCHMITT, OF FRANKFORT-ON-THE-MAIN, GERMANY.

DEVICE FOR FEEDING THE TOBACCO IN CIGAR-BUNCHING MACHINES.

1,102,692.

Specification of Letters Patent.

Patented July 7, 1914.

Application filed March 8, 1913. Serial No. 752,948.

To all whom it may concern:

Be it known that I, RUDOLF SCHMITT, engineer, a citizen of the German Empire, and resident of Frankfort-on-the-Main, 5 Germany, with the post-office address Rottlinstrasse 45, have invented new and useful Improvements in Devices for Feeding the Tobacco in Cigar-Bunching Machines, of which the following is a specification.

10 This invention relates to improvements in the cigar bunching machines to which the tobacco is supplied by placing the requisite quantity of tobacco in the hopper of the pressing device.

15 According to my invention the machine is provided with a fore-mold which serves to roughly shape the tobacco before it is submitted to the action of the press, said mold being made in two portions one of which 20 moves up and down with the jaws of the press while the other is carried by a lever which is swung to and fro over the hopper and actuated by a cam or the like. In addition, I provide a check device constituted 25 by a bell-crank lever, one limb of which locks the lever carrying the reciprocating half of the fore-mold when its other limb is no longer encountered by a pin on the slide owing to an accumulation of tobacco 30 in the press, said check device being an improvement on devices which are at present employed in cigar bunching machines of the kind in which the tobacco is fed to the press device by means of a belt con- 35 veyer and which come into operation and check the movement of the feed device when the tobacco accumulates, which devices are extremely complicated and correspondingly expensive and unreliable. The device of my 40 invention, on the other hand, is simple, cheap and absolutely reliable.

The invention is illustrated in the accompanying drawing wherein—

Figure 1 is a side elevation, Fig. 2 a section through the press device, Fig. 2^a a view of the sifting plate from above, and Fig. 3 a plan of the fore-mold. Fig. 4 shows the device in a different position from that represented in Fig. 1. Figs. 5, 6 and 7 show 45 the various cams for operating the device; and Fig. 8 is a cross section through the hopper, sifting plate and slide. 50

Above a table 1 rocks a lever 3, pivoted at 2 and carrying on its lower end at 4 the

one half of the fore-mold. The lever 3 is 55 provided with a spring 5 which tends to draw it inwardly and is forced out by a bar 6 which receives motion from the bell-crank lever 8 which is pivoted at 7. A lever 11, pivoted at 10, is connected to the 60 lever by a rod 9, the free end of said lever 11 carrying at 12 a roller which runs on the cam 13 which is separately shown in Fig. 6, a spring 14 keeping the roller in contact with the cam. The other half 15 of 65 the fore-mold (Fig. 3) is seated on the pressure member 16 carried by the lever 17, the latter being pivoted at 18 and subject to the action of a spring 19. Motion is transmitted to the lever 17 through a connecting rod 20, from the lever 22 pivoted at 21, the free end of this lever moving, by the aid of the roller 23, over the cam 24, which is separately shown in Fig. 5.

The pressure member 16 is provided, 75 underneath, with a trough 25 through which the slide 26 (Figs. 2 and 3) is adapted to pass. The reciprocating movement of the slide 26 is imparted through a bar 29 which is guided in a straight line at 27 and 28 80 and is operated by a push bar 31. The push bar is actuated by the bell-crank lever 33 which is pivoted at 32, and the free end of which runs, by the aid of a roller 34, over the triple cam 35 (Fig. 7). In this case 85 also, a spring 36 keeps the roller pressed against the cam 35.

The pressure member 16 moves up and down in a hopper 37, the bottom of which is formed by a sifting plate 38 (Fig. 2^a) 90 over which plate the slide 26 travels to and fro.

Another regulating device is provided in the form of a bell-crank lever pivoted at 39 and having one arm 40, situated within the 95 sphere of action of the pin 41 arranged on the push bar 31. The other arm 42 of this bell-crank lever serves as a locking arm for the lever 3 and prevents the same from moving when the arm 42 is in the position shown 100 by dotted lines in Fig. 1.

The device works in the following manner. In the first place all the parts being in the positions shown in Fig. 1, the tobacco is laid by hand between the two parts 4 105 and 15 of the fore-mold. On rotating the main shaft of the machine, the press jaw 16, and with it the half 15 of the fore-mold, is

lifted as shown in Fig. 4. At the same time the push bar 6, under the action of the corresponding operating cam, is moved rearward, so that the spring 5 brings the lever 3, and with it the half 4 of the fore-mold, into the position shown in Fig. 4, the tobacco thereupon falling out of the fore-mold into the hopper 37 on to the plate 38. The press jaw 16 then descends under the action of the cam 4 and compresses the tobacco, and at the same time all the dust falls through the holes in the sifting plate 38, that is to say is drawn off by an exhaust device connected with the sifting plate. The slide 26 now comes into operation and forces the tobacco out of the trough of the press jaw 16, on to the belt conveyer 43, which transports it to the bunching machine. During its forward movement, the pin 41 mounted on the push bar 31, strikes against the arm 40 of the bell-crank lever, thus causing the other arm 42 to take up the extended position shown in Figs. 1 and 4, so that the lever 3 is free to move. If however, the tobacco has accumulated in the press device or on the belt conveyer 43 to such an extent as to prevent the slide 26 from completing its stroke, the pin 41 fails to reach the arm 40 of the bell-crank lever, and consequently the other arm 42 of the said lever remains in the position indicated by dotted lines in Fig. 1, and prevents the lever 3 from moving. In such case this lever cannot discharge the tobacco lying in the fore-mold 4, 15, into the hopper, and the operator must refrain from placing any more tobacco in the fore-mold until the slide moves far enough forward to allow the pin 41 to encounter the bell-crank lever 40, thereby releasing the lever 3 and emptying the fore-mold into the hopper.

Now what I claim and desire to secure by Letters Patent is the following:

1. In devices for feeding the tobacco in cigar bunching machines the combination of the tobacco presser with a fore-mold made of two portions, of which the one moves up and down with the pressure jaw, while the other one rocks to and fro over the hopper of the press substantially as and for the purpose described.

2. In devices for feeding the tobacco in cigar bunching machines the combination of the tobacco presser with a fore-mold automatically discharging the tobacco into the hopper, which fore-mold is made of two por-

tions, of which the one moves up and down with the pressure jaw, while the other one rocks to and fro over the hopper of the press substantially as and for the purpose described.

3. In devices for feeding the tobacco in cigar bunching machines the combination of the tobacco presser with a fore-mold automatically discharging the tobacco into the hopper, which fore-mold is made of two portions, of which the one moves up and down with the pressure jaw, while the other one rocks to and fro over the hopper of the press moved by a cam or the like substantially as and for the purpose described.

4. In devices for feeding the tobacco in cigar bunching machines the combination of the tobacco presser with a fore-mold automatically discharging the tobacco into the hopper, which fore-mold is made of two portions, of which the one moves up and down with the pressure jaw, while the other one rocks to and fro over the hopper of the press moved by a cam or the like, and a checking device for preventing the movement of the one portion of the fore-mold substantially as and for the purpose described.

5. In devices for feeding the tobacco in cigar bunching machines the combination of the tobacco presser with a fore-mold and a checking device consisting of a bell-crank lever for preventing the movement of the fore-mold substantially as and for the purpose described.

6. In devices for feeding the tobacco in cigar bunching machines the combination of the tobacco presser with a fore-mold automatically discharging the tobacco into the hopper, which fore-mold is made of two portions, of which the one moves up and down with the pressure jaw, while the other one rocks to and fro over the hopper of the press moved by a cam or the like, and a checking device consisting of a bell-crank lever for preventing the movement of the one portion of the fore-mold substantially as and for the purpose described.

In testimony, that I claim the foregoing as my invention, I have signed my name in presence of two witnesses, this twenty fourth day of February 1913.

RUDOLF SCHMITT.
